ATTORNEY

UNITED STATES PATENT OFFICE.

ERWIN R. STOEKLE, OF MILWAUKEE, WISCONSIN, ASSIGNOR TO THE CUTLER-HAMMER MFG. CO., OF MILWAUKEE, WISCONSIN, A CORPORATION OF WISCONSIN.

THERMALLY-OPERATED CIRCUIT CONTROLLER.

Application filed September 12, 1921. Serial No. 500,017.

To all whom it may concern:

Be it known that I, ERWIN R. STOEKLE, a citizen of the United States, residing at Milwaukee, in the county of Milwaukee and 5 State of Wisconsin, have invented new and useful Improvements in Thermally-Operated Circuit Controllers, of which the following is a full, clear, concise, and exact description, reference being had to the accompanying drawing, forming a part of this 10 specification.

This invention relates to thermally operated circuit controllers and more particularly to such controllers of the fluid contact type.

In my Patent No. 1,499,420, dated July 1, 1924, is disclosed a circuit controller of the general character aforementioned and the present invention has among its objects that 20 of providing a modified controller of a similar type but possessing characteristics which render the same preferable for certain installations.

Another and more specific object is that 25 of providing such a circuit controller adapted under given or predetermined conditions to establish an electric circuit, rather than to interrupt an existing circuit.

Another object is that of providing such 30 a controller wherein provision is made for automatic interruption of the circuit established thereby following a given deviation from the aforementioned predetermined conditions.

Another object is that of providing such 35 a controller having parts providing an inherent time element in the operation thereof both for establishment and interruption of circuit and wherein the time elements for such respective actions may be varied either jointly or individually.

Other objects and advantages will hereinafter appear.

In the accompanying drawing, wherein 45 is illustrated an embodiment of the invention;

Fig. 1 is a vertical sectional view illustrating certain of the essential elements of the controller in detail, the relation of parts 50 being such that the controlled circuit is interrupted;

Fig. 2 is a similar view illustrating the relation between the controller element

proper and its support, the relation of parts being such that the controlled circuit is established; while,

Fig. 3 is a side elevational view of the complete device.

Referring to the drawing, the same illustrates a hermetically tight container composed of insulating and heat resisting material, such for example, as glass, and comprising an enlarged cylindrical portion or barrel 4, preferably arranged with its axis substantially horizontal, and a dependent 60 tubular extension 5 of relatively reduced diameter in open communication therewith. Said barrel is provided with internally located wells or pockets 6 and 7 spaced material and substantially equal distances from 70 the junction of the extension 5 with said barrel. Moreover the interior of said extension 5 is constricted adjacent the barrel as indicated at 8 and is enlarged beyond such constriction as indicated at 9 for purposes hereinafter explained.

Electrodes 10 and 11 are sealed within and preferably axially of the barrel 4 of the container, said electrodes having terminal portions located within the respective wells 6 80 and 7 and being also provided with portions penetrating the outer walls of the container there to be permanently and electrically connected respectively with suitable conductive caps 12 and 13 which in practice are cemented or otherwise permanently secured to and preferably about projecting reduced portions of the barrel substantially as illustrated.

A quantity of conductive fluid 14, which is liquid at working temperatures, 90 such for example as mercury, is contained within the extension 5, filling the latter substantially to the junction thereof with the barrel 4, whereas, in practice the wells 6 and 7 are likewise filled up to the level of the 95 interior of said barrel with similar conductive fluid, such latter mentioned bodies of fluid surrounding and submerging the associated terminal portions of the respective electrodes 10 and 11 but being electrically 100 discontinuous with reference to one another under the conditions illustrated in Fig. 1.

A heating element, such for example as a resistance coil 15, is arranged adjacent to and preferably about the internally enlarged 105 portion 9 of the extension 5 for subjecting

the conductive fluid contained therein to thermic influence variable with the degree of heat developed by said heater.

Thus following a predetermined degree of heating of the fluid within the enlarged chamber 9 vaporization occurs, whereupon that portion of the fluid column located above such vaporized portion is suddenly ejected from the extension and within the barrel 4 there to unite with the reduced bodies of fluid located within the respective wells 6 and 7 for establishing electrical conductivity therebetween and between the immersed electrodes whereby circuit between said electrodes is established.

Following a given degree of cooling of the fluid remaining in the extension 5 the ejected liquid fluid is adapted to flow back within said extension, separating itself from the bodies of fluid within the respective wells for sudden interruption of circuit therebetween.

In practice the space within the container not occupied by the conductive elements may preferably be evacuated or filled with a suitable arc suppressing gaseous medium.

The diameter of the constricted portion 8 of the extension 5 is so chosen as to permit the aforescribed reflux of the ejected fluid while at the same time restricting free circulation and boiling of the column of fluid under action of the heater, whereby the heated portion of the fluid is subjected to a hydrostatic head equal to the height of the column located thereabove. Thus actual vaporization is delayed but when once initiated serves to expel liquid from the extension with consequent reduction in the aforementioned hydrostatic head such that the vaporization when initiated progresses with great rapidity and results in sudden and complete expulsion of the supernatant liquid fluid.

Further it may be here observed that the aforescribed enlargement of that portion of the fluid column adjacent the heater serves to provide in the action of the controller a time element during which such enlarged body of fluid is heated to the vaporization point under the aforementioned conditions of increased pressure.

Obviously by varying the diameter of the enlarged portion of the tubular extension the response of the device may be retarded or accelerated practically at will, whereas, by varying the number of turns of the heater coil 15 or by changing the diameter of said coil or otherwise altering the heat exchange relation of the heater to the fluid to be heated thereby the response characteristics of the device may be further varied between relatively wide limits. Also it is to be observed that variations in diameter of the constricted portion 8 of the tubular extension serve to vary the time element incident

to re-interruption of the controlled circuit without materially varying the timing element incident to establishment of such circuit.

Referring now to Fig. 2 of the drawing, the same illustrates a controller element and heater coil such as those just described together with a support therefor, which support in practice may be specially designed to effect further control, calibration or variation of the period of response of the device.

Such support may preferably comprise a pair of similar complementary sections 16 and 17 composed of insulating and heat absorbent material adapted to interfit with one another as illustrated particularly in Fig. 3 to form therebetween and therewithin a suitable space for reception of said controller element and coil.

In practice said sections 16 and 17 are provided with complementary recessed portions 18 and 19 forming together a chamber to receive the coil 15 and with further complementary recesses or grooves 20 and 21 forming together a bore leading outwardly from said recess for reception of the tubular extension 5, the latter penetrating within the aforementioned enlarged chamber and preferably within the coil contained in the latter. Further the adjacent upper portions of sections 16 and 17 are cut away to form therebetween a horizontally extending recess to receive the barrel 4 of the controller element while providing for ready removal of the control element from the support.

In practice pairs 22 and 23 of conductive and preferably resilient clips are secured to and between the sections 16 and 17 by means of bolts 24 and 25, the latter serving in conjunction with similar bolts 26 and 27 to secure said sections 16 and 17 in assembled relation, all of said bolts being insulated from one another by the substance of said sections 16 and 17. The aforescribed pairs of clips 22 and 23 are so arranged as to permit insertion of the respective end caps 12 and 13 therebetween and to firmly and resiliently retain the same in such position when so inserted, whereas obviously the outer portions of the respective bolts 24 and 25 may be employed as exterior terminals for the respective electrodes 11 and 10 as illustrated. Similarly the terminal portions of the heater coil 15 may be led through suitable passages within the support sections 16 and 17 to the respective bolts 26 and 27 and arranged in electrical connection with the latter whereby said bolts may likewise be employed as exterior terminal devices for the heater coils also as illustrated.

Owing to the aforementioned heat absorbing characteristics of the support, it is apparent that by varying the design thereof particularly the size and contour of its in-

- ternal chamber and passage, the same may be adapted to absorb different proportions of heat produced by the heater 15, thereby providing further means for calibration of the time element of response of the device whereas obviously different proportions of the total heat liberated will be absorbed by the support for different values of the developed heat.
10. The aforescribed mechanism thus provides for positive establishment of circuit following the occurrence of predetermined thermic conditions and for positive and sudden interruption of the circuit so established following a given deviation from such predetermined conditions, which conditions, as well as the time elements incident to such circuit commutations may be varied through changes in adjustment and in design of the structure.
- Obviously if desired the heater coil may be connected in the controlled circuit thus adapting the device to act as an overload relay, or optionally said coil may be arranged in a separate circuit.
- What I claim as new and desire to secure by Letters Patent is:
1. A circuit controller comprising a plurality of substantially stationary fluid contacts and a quantity of conductive fluid to be elevated for effecting physical union with said contacts jointly to thereby establish electrical conductivity therebetween.
  2. A circuit controller comprising a plurality of substantially stationary fluid contacts and a quantity of conductive fluid to be subjected to influence of fluid pressure for elevation thereof to effect physical union with said contacts jointly to thereby establish electrical conductivity therebetween.
  3. In a circuit controller, the combination with a plurality of substantially stationary fluid contacts having individual circuit terminals, of a quantity of conductive fluid and means for causing said fluid to ascend and unite with said fluid contacts jointly for establishing electrical conductivity therebetween.
  4. In a circuit controller, the combination with a plurality of fluid contacts having individual circuit terminals, of a quantity of conductive fluid and means for subjecting said fluid to influence of fluid pressure for causing said fluid to unite with said fluid contacts jointly for establishing electrical conductivity therebetween.
  5. In a circuit controller, the combination with a plurality of fluid contacts having individual circuit terminals, of a quantity of conductive fluid and means for subjecting said fluid to influence of fluid pressure of its own vapor causing said fluid to unite with said fluid contacts jointly for establishing electrical conductivity therebetween.
  6. In a circuit controller, the combination with a plurality of fluid contacts and substantially stationary means for supporting the same in insulated relation to one another, of a separate body of conductive fluid also carried by said supporting means, the latter having associated means for causing said fluid to unite with said contacts jointly for establishing electrical conductivity therebetween.
  7. In a circuit controller, the combination with a plurality of fluid contacts and means for supporting the same in insulated relation to one another, of a quantity of conductive fluid also carried by said supporting means, the latter having associated means including a heater for subjecting said fluid to pressure of its own vapor for causing the fluid to effect electrical engagement with said contacts jointly.
  8. In a circuit controller, the combination with a plurality of fluid contacts and means for supporting the same in insulated relation to one another, of a quantity of conductive fluid also carried by said supporting means, the latter having associated means including a heater for subjecting said fluid to fluid pressure of its own vapor for causing the fluid to effect electrical engagement with said contacts jointly, said support having parts providing for subsequent separation of fluid from the fluid constituting said contacts for interruption of circuit between the latter.
  9. In a circuit controller, the combination with an insulating support having a plurality of spaced wells and a dependent hollow extension, of fluid contacts carried within the respective wells, a quantity of conductive fluid to be contained within said extension, the latter being internally provided with a constricted portion adjacent to said wells and with an interiorly located enlarged portion and a heater to act upon the fluid within said enlarged portion of said extension for effecting vaporization of a portion of the fluid to thereby expel a portion of the fluid from said extension and into intimate fluid engagement with said contacts jointly to thereby complete circuit therebetween.
  10. In a circuit controller, the combination with an insulating support having a plurality of spaced wells and a dependent hollow extension, of fluid contacts carried within the respective wells, a quantity of conductive fluid to be contained within said extension, the latter being internally provided with a constricted portion adjacent to said wells and with an interiorly located enlarged portion and a heater to act upon the fluid within said enlarged portion of said extension for effecting vaporization of a portion of the fluid to thereby expel a portion of the fluid from said extension and into intimate fluid engagement with said contacts jointly to thereby complete circuit therebetween.

tween, said constricted portion of the extension being adapted to permit reflux into the extension of a quantity of fluid substantially equal to that so expelled following a given degree of cooling of the heated fluid.

11. In a circuit controller, the combination with a plurality of fluid contacts and means for supporting the same in insulated relation to one another, of a quantity of conductive fluid also carried by said supporting means, the latter having associated means

including a heater for subjecting said fluid to fluid pressure of its own vapor for causing the fluid to effect electrical engagement with said contacts jointly, and an insulating and heat absorbent holder for said parts comprising similar sections uniting in a common plane. 15

In witness whereof, I have hereunto subscribed my name.

ERWIN R. STOEKLE.
